(57) **CLAIM**

The ornamental design for a window air conditioner, as shown and described.

DESCRIPTION

FIG. 1 is a front view of a window air conditioner, showing our new design;

FIG. 2 is a back view of the window air conditioner shown in FIG. 1;

FIG. 3 is a top view of the window air conditioner shown in FIG. 1;

FIG. 4 is a bottom view of the window air conditioner shown in FIG. 1;

FIG. 5 is a first side view of the window air conditioner shown in FIG. 1;

FIG. 6 is a second side view of the window air conditioner shown in FIG. 1;

FIG. 7 is a perspective view of the window air conditioner shown in FIG. 1; and,

FIG. 8 is another perspective view of the window air conditioner shown in FIG. 1.

The broken lines shown in the drawings represent portions of the window air conditioner that form no part of the claimed design.

1 Claim, 8 Drawing Sheets
